UNITED STATES PATENT OFFICE.

WILLIAM JOHN PHILLIPS, OF BROOKLYN, NEW YORK.

BOTTLE-SUPPORT.

1,325,860.

Specification of Letters Patent. Patented Dec. 23, 1919.

Original application filed March 21, 1919, Serial No. 284,154. Divided and this application filed May 20, 1919. Serial No. 298,479.

To all whom it may concern:

Be it known that I, WILLIAM JOHN PHILLIPS, a citizen of the United States, residing at Brooklyn, in the county of Kings and State of New York, have invented certain new and useful Improvements in Bottle-Supports, of which the following is a full, clear, and exact specification.

This invention relates to supports for attaching receptacles, such as babies' bottles, to a crib or carriage in position for use, and it has for its object to provide improved means for adjustably fastening such a receptacle or bottle to a fixture so that the baby can take the contents without the necessity of some person remaining on hand to hold said receptacle or bottle. Other objects will appear as the description proceeds.

The invention will be first hereinafter described in connection with the accompanying drawings, and then more specifically defined in the claims at the end of the description.

In the accompanying drawings, wherein similar reference characters are used to designate corresponding parts throughout the several views:—

Figure 1 is an elevation of the bottle receptacle with the cover in place and showing the attaching clamp.

Fig. 2 is a longitudinal vertical section of the receptacle, showing the bottle therein, and the cavity in the cover for holding a nipple.

Fig. 3 is an enlarged elevation of the supporting bracket which is adjustable along the receptacle.

Fig. 4 is a cross section through the middle portion of the receptacle, on the line VI—VI of Fig. 1.

Fig. 5 is a section on the line VII—VII of Fig. 5, and

Fig. 6 is a section on the line VIII—VIII of Fig. 5.

The receptacle 1 is preferably made substantially as illustrated in my pending application for bottle holder, Ser. No. 284,154, filed March 21, 1919, of which this application is a division. Said receptacle is cylindrical to conform to the prevailing style of baby's nursing bottle, and a cover 2 is formed to correspond. The receptacle is composed of outer and inner casings 3 and 4 which may be of papier mâché or other suitable material, and which are spaced

apart by one or more rings 5 so as to form an air space between said casings. The bottoms of the casings are separated by crossed ribs 6. Within the inner casing is a layer of felt 8, and the mouth of the receptacle 60 may be finished off with a ring 7 covering the air space between the inner and outer casings and the upper edge of the felt lining.

The cover also comprises inner and outer casings 10 and 11 spaced apart by one or more rings 12, and has a layer of felt 14. The lower edge of the cover may be finished off by a ring 13 covering the air space between the inner and outer casings and the 70 felt layer. The outer casing 10 extends down half an inch or so below the ring 13 and is designed to fit snugly over the upper edge portion of the receptacle 1, as shown in Fig. 2. In the top of the cover 75 there is formed a tray 15 in which one or more nipples 19 may be conveniently stored. A snap closure 16 is hinged at 17 to the cover for closing the tray or storage space 15, and said hinge is preferably equipped 80 with a spring 18 for normally holding the closure shut.

The receptacle 1 is adapted to hold a baby's nursing bottle 9 and maintain the original temperature of the contents while 85 being carried around, so that when the times arrive for feeding the baby the milk will still be warm. The provision of the tray or storage space for the nipples in the cover is of great convenience for keeping said nipples 90 clean and always at hand when needed.

For attaching the receptacle to a carriage or crib, or other fixture (not shown), either when in use or when not in use, an adjustable clamp is provided. Said clamp comprises a plate 22 having a pair of interlocking members 21 and 31 engaging in a slotted plate 20 suitably secured to the inner surface of the outer casing 3 of the receptacle so as to extend longitudinally of the same for a 100 considerable distance, the slot in the plate 20 registering with a similar slot in said casing, as shown in Fig. 5. The plate 22 has a rotatably adjustable disk 23 mounted thereon, and from said disk there extend a pair 105 of spring arms 24 hinged to the disk at 25 and each carrying a clamping bolt 26 having a concave engaging end piece 28. The two arms 24 are hinged in line with each other so that they may be swung together to as- 110

sume different positions with respect to the plate 22 and disk 23 without changing their relative positions to each other. The hinges may have sufficient frictional contact between their members to maintain the arms in any position to which they may be set. The bolts 26 may be adjusted to engage a part of a carriage or crib, and by tightening up on said bolts the spring arms may be placed under sufficient tension to hold the receptacle in the desired position on said part. The disk 23 also has friction contact with the plate 22 so as to retain said disk in the position in which it may be set.

15 It will thus be seen that the clamping arms may be swung upon the disk 23, while said disk may be rotated on the plate 22, and said plate may be adjusted longitudinally on the receptacle, giving a wide range 20 of adjustments for holding the receptacle at any desired angle or position on the carriage, crib, or other supporting means. The plate 22 is held frictionally in set position in the slotted strip 20, and to increase this 25 frictional contact the interlocking members 21 and 31 are spaced at a distance apart, the latter member being preferably carried by a depending tongue 29 at the lower edge of the plate and having a reduced neck 30 to 30 pass through the slotted strip while the lateral edges of the tongue engage the margins of the slot, as at 32 in Fig. 5, and have a clamping action thereon.

Having thus described my invention, what

I claim as new and desire to secure by Letters Patent of the United States is:—

1. The combination with a receptacle of the character described, of a plate adjustable longitudinally of the receptacle, a disk adjustable rotatably on the plate, and clamp- 40 ing arms hinged on said disk.

2. The combination with a receptacle of the character described, of a plate adjustable longitudinally of the receptacle, a disk rotatably mounted on the plate, and a pair of 45 clamping arms hinged to the disk, the hinges of said arms being in line with each other for the purpose specified.

3. The combination with a receptacle of the character described, of a plate adjustable 50 longitudinally of the receptacle, a disk rotatably mounted on the plate, a pair of spring clamping arms on the disk, and clamping bolts adjustably mounted on the end portions of said arms.

4. The combination with a receptacle of the character described, of a plate adjustable longitudinally of the receptacle, the latter having a slot, a pair of interlocking members on the plate engaging said slot, one of said 60 members depending from the lower edge of the plate and having laterally extending edges to engage the margins of the slot, and clamping means on the plate.

In testimony whereof I have signed my 65 name to this specification.

WILLIAM JOHN PHILLIPS.
